UNITED STATES PATENT OFFICE

167,032

TILE BLOCK

Richard J. Galvin, Sheffield, Iowa

Application February 6, 1952, Serial No. 18,417

Term of patent 14 years

(Cl. D18—2)

To all whom it may concern:

Be it known that I, Richard J. Galvin, a citizen of the United States, residing at Sheffield, in the county of Franklin and State of Iowa, have invented a new, original, and ornamental Design for a Tile Block, of which the following is a specification, reference being had to the accompanying drawing, forming a part thereof.

Fig. 1 is a perspective view of my tile block showing my new design;

Fig. 2 is a bottom view; and

Fig. 3 is an enlarged longitudinal sectional view taken on line 3—3 of Fig. 1, showing my new design.

I claim:

The ornamental design for a tile block, substantially as shown.

RICHARD J. GALVIN.
